UNITED STATES PATENT OFFICE.

JOHN WRIGHT, OF HOOSICK FALLS, NEW YORK.

DESIGN FOR A WHISK-BROOM HANDLE.

SPECIFICATION forming part of Design No. 17,425, dated June 28, 1887.

Application filed May 13, 1887. Serial No. 238,142. Term of patent 7 years.

To all whom it may concern:

Be it known that I, JOHN WRIGHT, a citizen of the United States, residing at Hoosick Falls, in the county of Rensselaer and State of New York, have invented a certain new and useful Design for Whisk-Broom Handles, of which the following is a description.

The leading feature of my design is a representation of a tree having spreading branches, ensconced in which is a bird's nest filled with eggs.

A represents the handle of the broom, which is formed in a rustic design, like the trunk of a tree, B; and C represents the shield or socket portion, over which the branches radiating from the trunk and handle spread, as shown at D. Numerous small branches and foliage spread from the larger branches, and ensconced between the branches is a bird's nest, E, filled with eggs.

I use the term "rustic" as indicating a shrub or tree like appearance.

What I claim is—

1. The design for broom-handles herein shown and described, the same consisting of a rustic handle, B, and shield C, having the branches D radiating thereover and foliage extending from the same.

2. The design for broom-handles herein shown and described, the same consisting of a rustic handle, B, and shield C, having the branches D radiating thereover and foliage extending therefrom, and the nest E, ensconced therein.

JOHN WRIGHT.
